CLAIM

The ornamental design for a towel bar, as shown and described.

DESCRIPTION

FIG. 1 is a perspective view of a towel bar showing my new design;

FIG. 2 is a top plan view thereof;

FIG. 3 is a front elevation view thereof;

FIG. 4 is an end view thereof, the opposite end being a mirror image of the end shown;

FIG. 5 is a bottom plan view thereof; and,

FIG. 6 is a rear view thereof.

It is understood that FIGS. 1, 2, 3, 5 and 6 are shown broken away to indicate indeterminate length.
